CLAIM

The ornamental design for a market stand, as shown and described.

DESCRIPTION

FIG. 1 is a front, left perspective photographic view of a market stand showing our new design;

FIG. 2 is a front photographic view thereof;

FIG. 3 is a right side photographic view thereof;

FIG. 4 is a left side photographic view thereof; and,

FIG. 5 is a top photographic view thereof.

The broken lines depicting the remainder of the market stand form no part of the claimed design.

1 Claim, 5 Drawing Sheets
